UNITED STATES PATENT OFFICE.

JOSEPH S. LEWIS, OF MILTON, PENNSYLVANIA.

KEY-RING.

SPECIFICATION forming part of Letters Patent No. 739,094, dated September 15, 1903.

Application filed May 11, 1903. Serial No. 156,677. (No model.)

To all whom it may concern:

Be it known that I, JOSEPH S. LEWIS, a citizen of the United States, residing at Milton, in the county of Northumberland and State 5 of Pennsylvania, have invented a new and useful Key-Ring, of which the following is a specification.

This invention relates to certain improvements in key-rings, and has for its principal 10 object to provide a novel form of ring from which the key or keys cannot be removed without considerable difficulty, the device to some extent being in the nature of a puzzle and applicable to ring structures generally, 15 and although principally intended for the reception of keys the bow of the key may be replaced by an article of any similar construction and the device placed on the market as a puzzle.

With this and other objects in view the invention consists in the novel construction and arrangement of parts hereinafter described, illustrated in the accompanying drawings, and particularly pointed out in the appended 25 claims, it being understood that various changes in the form, proportions, size, and minor details of the structure may be made without departing from the spirit or sacrificing any of the advantages of the invention.

In the accompanying drawings, Figure 1 is 30 an elevation of the device, illustrating the ring in position thereon. Fig. 2 is a similar view showing the first step in the removal of the key. Figs. 3 and 4 further illustrate the method of removal of the key. Fig. 5 is a sectional plan view of the ring on the line 5 5 of Fig. 3.

Similar numerals of reference are employed to indicate corresponding parts throughout the several figures of the drawings.

The ring is formed of spring-wire bent somewhat in the form of a trefoil and comprising 40 three interlacing loops 1, 2, and 3, the wire crossing alternately over and under the portions which form the loops and the ends of 45 the wire being brought together at 4.

In following out the construction of the ring, starting from 4, the wire is curved to form the first loop 1 and thence to form the second loop 2. The wire passes first under and then over 50 the loop 1 and thence under the loop 2 to the point of starting. The two ends are provided

with beveled portions, and these beveled portions overlap and are held closely together by the inherent spring tendency of the wire, as well as from the fact that the two end portions pass on opposite sides of the loop 2, and are thus held in engagement with each other by said loop. 55

In the present instance a single key 5 is shown on the ring, the bow of the key receiving the outer portion of loop 2. To remove the key, it is necessary to first pass the key-shank through the space formed by separating the beveled ends of the ring. The key is now in such position that its shank crosses the 60 general diametral line of the ring, the parts assuming the position shown in Fig. 2, with the bow of the key engaging the outer portion of the loop 2, while the shank is in front of the adjacent end portions of the loops 1 65 and 3 and thence extends inward through the central portion of the ring, its lower portion being to the rear of the lower portions of the loops. In this position the key is moved in the direction of the arrow until it assumes the 70 position shown in dotted lines in Fig. 3, after which the key is turned, so that the bow may be slid to the position shown in Fig. 4, and from thence readily disengaged from the ring by passing the bow between the ends 4. 75

In place of the trefoil arrangement illustrated the ring may be in the form of a quatrefoil or cinquefoil, the construction otherwise remaining the same.

With a device of this character it becomes 80 exceedingly difficult for a person to detach a key from a ring unless first acquainted with the construction of the device, while at the same time the cost of construction is no greater than that of the common form of key-ring. 85 The device is further advantageous in that by crossing the end portions of the ring or disposing the same on opposite sides of the adjacent loop the beveled and overlapping ends will be held in closer engagement with 90 each other than where no auxiliary means are employed for holding the ring in locked or closed position. 95

Having thus described the invention, what is claimed is—

1. A key-ring formed of a piece of wire bent in the form of a plurality of loops of which 100

each loop interlaces with all of the other loops, the ends of the wire being brought together to form a joint.

2. A key-ring formed of a piece of wire bent in the form of a plurality of crossing and interlacing loops, the ends of the wire being brought together to form a joint.

3. A key-ring formed of a piece of wire bent into the form of a plurality of crossing and interlacing loops, the ends of the wire being beveled and overlapping, and the wire adja-

cent to the ends being disposed on opposite sides of one of the loops, thereby to assist in holding such ends closely together.

In testimony that I claim the foregoing as my own I have hereto affixed my signature in the presence of two witnesses.

JOSEPH S. LEWIS.
